Design No. 13,732, dated March 13, 1883.

UNITED STATES PATENT OFFICE.

GASPARD WEISS FRIES, OF PARIS, FRANCE, ASSIGNOR TO JUDA SOLOMON,
SIMEON SOLOMON, AND SALOMON SOLOMON, OF NEW YORK, N. Y.

DESIGN FOR CRETONNE.

SPECIFICATION forming part of Design No. 13,732, dated March 13, 1883.

Application filed January 6, 1883. Term of patent 3½ years.

To all whom it may concern:

Be it known that I, GASPARD WEISS FRIES, of Paris, in the Republic of France, have invented a new and original Design for Curtains, Furniture-Covers, &c., of which the following is a specification.

The accompanying photograph illustrates a face view of my new design.

This invention relates to a new design for an impression, print, or picture to be printed, painted, or otherwise worked into woven fabrics used for window-curtains, furniture-covers, and the like, the fabric so impressed being known in the trade as "cretonnes."

The invention consists in the new ornamentation and configuration of figures hereinafter described.

On the background is the representation of a castle, *o*, and of a castellated gate, *r*. In front of this is foliage *v* on the representations of trees *s*. Between these trees, and beneath this foliage, is an open space, to which the castle *o* and the gate *r* constitute the background, and in this open space are the representations of female figures *B*, facing each other and performing a dance on a rug or carpet. Directly behind these representations of female figures

B are groups *e* and *f* of orientally-clad soldiers, and to the left of the latter mounted soldiers *d*. A figure, *A*, appearing to represent a royal personage, is at the left above a growth of cactus, *g*, and near it is the representation of a pipe, *i*. On the right of the gateway *r* are groups *a* and *C* of soldiers, near which groups are representations of shrubs, *n*. Above the group *d* of mounted men in the foliage *v* are the representations *b* and *c* of an Indian man and woman, respectively.

I claim—

1. The design for a woven fabric or cretonne, the same consisting of the representation of the figure *B*, substantially as shown.

2. The design for a woven fabric or cretonne, the same consisting of the figures *v*, *s*, *o*, *r*, *B*, *e*, *f*, *d*, *A*, *g*, *i*, *a*, *C*, and *n*, substantially as shown.

3. The design for a woven fabric or cretonne, the same consisting of the figures *v*, *s*, *o*, *r*, *B*, *e*, *f*, *d*, *A*, *g*, *i*, *a*, *C*, *n*, *b*, and *c*, substantially as shown.
